CLAIM

The ornamental design for a fireplace insert for holding material to be burned, as shown and described.

DESCRIPTION

FIG. 1 is a top perspective view of a fireplace insert for holding material to be burned, showing my new design;

FIG. 2 is a front elevation view thereof;

FIG. 3 is a rear elevation view thereof;

FIG. 4 is a side elevation view thereof, the opposite side being a mirror image of that shown;

FIG. 5 is a top plan view thereof; and

FIG. 6 is a bottom plan view thereof.
